DUST SEPARATOR

William R. Appeldoorn, Detroit, Mich.

Application September 9, 1943, Serial No. 501,616

2 Claims. (Cl. 183—36)

(Granted under the act of March 3, 1883, as
amended April 30, 1928; 370 O. G. 757)

The invention described herein may be manufactured and used by or for the Government for governmental purposes, without the payment to me of any royalty thereon.

The present invention pertains to a novel dust separator for removing dust and other particles from a gas such as air. One of the specific applications of the device is its use as an air cleaner in connection with the interior of a combat tank. Other uses will readily suggest themselves.

The principal object of the invention is to provide a compact and efficient apparatus of this character. In a combat tank, economy of space is a prime consideration.

The air passage in the apparatus is annular and preferably conical, converging towards the outlet end. Air is drawn by a fan into the larger end and, by means of suitable whirler blades, is given a large rotational component. The diminishing means circumference of the passage accelerates the current and increases the centrifugal force which throws the particles outward. At the outlet the laden portion of the air is communicated to a scroll and discharged therefrom. The remainder of the air enters another chamber or duct having turning vanes which restore the stream from a whirling to a linear path. The removal of the turbulence in this manner diminishes the kinetic energy of the air and likewise the power input requirement of the fan, as described more fully hereinafter.

An illustrative embodiment of the invention is described in the following specification and shown in the accompanying drawings in which:

Figure 1 is a longitudinal section of the device on the line 1—1 of Figure 2;

Figure 2 is a plan view, showing the housing in section;

Figure 3 is a section on the line 3—3 of Figure 2, and

Figure 4 is an end view.

The apparatus is built within a housing including a cylindrical outer wall 1 from one end of which extends a converging conical wall 2. Within the cylindrical wall is mounted a fan rotor 3 driven by a motor 3' and carrying at its periphery a cylinder 4 concentric with and spaced from the wall 1. The cylinder 4 is not co-extensive with the wall 1 towards the wall 2, and the intervening space is occupied by a fixed cylindrical wall 5 held by a suitable partition 6. At the opposite end, the wall 4 is formed with an inwardly directed curved lip 7 over which air flows to the chamber 8 between the cylinders 1 and 4. In this chamber a number of suitably shaped fan

blades 9 are carried by the wall 4 and are designed to draw air into the chamber 8.

The annular chamber 10 between the cylindrical walls 1 and 5 contains a number of suitably curved whirler blades 11 secured preferably to the inner surface of the wall 1. The blades are designed to increase the rotational component of the air stream and to discharge it with a whirling motion. From the wall 5 another conical wall 12 extends within and parallel to the wall 2 and forms therewith a tapering chamber 13 in which the whirling stream is accelerated.

At the smaller or discharge end of the chamber 13 is built a scroll 14 joining the smaller end of the conical wall 2 at the point 15. The scroll is coaxial with the rotor 3 so that the direction of flow therein is transverse of the chamber 13. No substantial change of direction occurs in the transfer of air from the chamber 13 to the scroll, due to the large whirling or rotational component of the stream in the chamber 13.

A cylindrical wall 16 extends from the smaller end of the conical wall 12, and around the wall 16 is spaced a concentric wall 17 flaring in the outward direction. A comparatively small space 18 is retained between the walls 2 and 17 for a purpose which will presently appear. In the chamber 19 between the walls 16 and 17 are mounted turning vanes 20 designed to direct the air from the chamber 13 into a substantially linear path.

In the operation of the device the dirt particles in the whirling air in the chamber 13 are thrown towards the wall 2 by centrifugal force. The space 18 is dimensioned to pass about 20 per cent of the total air from the chamber 13 to the scroll 14. This air, being the outer fraction, carries practically all of the dirt and is discharged from the outlet 21 of the scroll as shown in Figure 4.

The remaining, clean air is discharged from the larger end of the chamber 19 into the space or apparatus where it is to be used. This air, being relieved of its turbulence, is also relieved of much of its kinetic energy. Consequently, the power input requirement at the fan is less, for a given volume of air, than if the discharged air were allowed to remain turbulent, and the efficiency of the apparatus is thereby improved.

One of the characteristics contributing to the compactness of the apparatus is the converging chamber 13 wherein the air is accelerated and the centrifugal force increased for more efficient separation of the solid particles.

While a specific embodiment of the invention has been illustrated and described, it is intended that various alterations in the details of con-

struction may be made without departing from the invention as indicated by the scope of the appended claims:

What I claim is:

1. A dust separator comprising a housing having a conical wall, a core within said housing having a conical wall spaced from and parallel to the conical wall of said housing and cooperating therewith to form an annular tapering passage of gradually decreasing cross-sectional area, a fan at the larger end of said passage for drawing air thereinto, whirler blades adjacent the discharge side of said fan to impart a whirling motion to the air to throw the dust particles in the air radially outwardly in the passage, a scroll at the smaller end of the conical wall of said housing, said scroll having an annular opening communicating with the outer portion of the annular tapering passage to receive dust laden air, a double walled structure within said scroll and communicating with the inner portion of said passage, and turning vanes in said structure adapted to redirect the whirling air into a linear path.

2. A dust separator comprising a housing having a cylindrical wall and a conical wall of de-

creasing cross-sectional dimension extending from the cylindrical wall, a core within said housing having a conical wall spaced from and parallel to the conical wall of said housing to form an annular-tapered passage of gradually decreasing cross-sectional area, a fan motor housed within said core, a fan blade on said motor and within said cylindrical wall for drawing air into said passage, whirler blades adjacent the discharge side of said fan blade to impart a whirling motion to the air to throw the dust particles in the air radially outwardly in the passage, a scroll at the smaller end of the conical wall of said housing, said scroll having an annular opening communicating with the outer portion of the annular tapering passage to receive dust laden air, a cylindrical wall extending from the smaller end of the conical wall of said core, a shell surrounding said last mentioned cylindrical wall and spaced therefrom to form an annular passage communicating with the radially inner portion of the tapering passage between the two conical walls, and turning vanes in said last defined passage adapted to redirect the whirling air into a linear path.

WILLIAM R. APPELDOORN.
